POWER-REGULATING APPARATUS.

1,225,620.

Specification of Letters Patent.

Patented May 8, 1917.

Application filed April 16, 1913. Serial No. 761,470.

To all whom it may concern:

Be it known that I, JAMES C. HAGEY, a citizen of the United States, residing at Chicago, in the county of Cook and State of Illinois, have invented a certain new and useful Improvement in Power-Regulating Apparatus, of which the following is a full, clear, concise, and exact description, reference being had to the accompanying drawings, forming a part of this specification.

My invention relates to power regulating apparatus.

Prominent objects of the invention are to provide a simple, practical and effective power regulating or controlling apparatus; to arrange for the adjustment of the power to the requirements or needs of the apparatus or instrument with which the apparatus is associated; to secure such adjustment of power automatically if desired; to permit the effective power, which is adjusted to the needs or requirements of the associated apparatus or instrument, to be changed or varied at will; and to accomplish the foregoing and other desirable results in a simple and expeditious manner.

In this application, I have shown my invention applied to a pneumatically operated musical instrument player, such, for example, as a player piano or piano player, but it will be understood that the invention is not limited to application to such instrument, nor, in fact, is it limited to musical instruments at all, being applicable to a wide variety of devices, instruments and apparatus.

In the accompanying drawings, Figure 1 is a view, somewhat diagrammatic of a portion of an automatic playing device for musical instruments embodying my present invention;

Fig. 2 is a longitudinal sectional view of a slightly modified arrangement, the tracker being omitted from this figure;

Fig. 3 is a view, similar to Fig. 2, of a further modification;

Figs. 4, 5, 6, 7 and 8, are views, more or less diagrammatic, of further modifications.

Referring first to Fig. 1, I show a tracker 1, having the usual set of apertures 2—2 and also having an extra set of apertures

3—3 which are preferably the same in number as those of the usual set and located individually directly in the rear of the same. The apertures 3—3 are in communication 55 with a common duct or passage 4 running lengthwise of the tracker and communicating with a pipe 5, to which is connected a flexible tube 6. The tube 6 extends to certain apparatus suitably located in the instrument at a proper distance from the tracker. This apparatus comprises a small pneumatic 7 having a swinging leaf 8 and a large pneumatic 9 having a swinging leaf 10 on which the pneumatic 7 is mounted, a 65 board 11 being preferably interposed between the pneumatics 7 and 9. The pneumatic 9 is mounted, in turn, upon some convenient part of the instrument, as, for example, by securing the base 12 thereof to a 70 rigid structure 13. The tube 6 runs directly to the pneumatic 7 and communicates with the interior thereof. Said pneumatic 7 contains a swinging valve 15 having a bleed 15^a, which valve has a hinged connection with a block 16 secured to the base 17 of said pneumatic 7. The other end of the valve 15 has a link connection with the swinging leaf 8 of the pneumatic 7, by means of a pivoted link 18. The valve 15 80 controls a port 19 in the base 17 and board 11, said port 19 consequently communicating with the interior of the large pneumatic 9, the board 11 covering a cut-away portion 20 in the leaf 10 of said pneumatic 9. 85 Within the large pneumatic 9 is arranged another swinging valve 21 having a bleed 21^a, which valve 21 controls a large port 22 in the base 12, said valve 21 forming the movable leaf of a pneumatic 21^b mounted 90 on an arm 21^c secured to the base 12. The swinging end of the valve 21 is connected by a link or rod 23, which extends through an opening 24 in the board 11, to a swinging link 25, the left hand end of which 95 is pivotally connected to a long arm 26 which is, in turn, pivotally connected to a standard 27 mounted upon the swinging leaf of the pneumatic 9. The other end of the link 25 is pivotally connected with a clip 100 or lug 28 on the swinging leaf 8 of the small pneumatic 7. The free end of the swinging

arm 26 is connected with a longitudinally adjustable rod 29, which latter is understood to be a controlling rod for manual or automatic control and to extend to some suitable controlling device for purposes hereinafter to be explained. The port 22 is understood to lead to the apparatus for reducing air pressure and another port 30 is understood to lead to the action, the arrangement thus described therefore being suitably interposed so as to control the pressure of air applicable to the action. A spring 31 is connected to the swinging leaf of the large pneumatic 9 and extended to a suitable support or tension member 32 carried by a supporting strip 33, a pin 34 being provided to vary the tension of the spring 31 and thereby vary the tension applicable to the reduced air pressure. Another spring 35 is connected to the end of the link 25 and extended to a tension block 36 having a pin 37 to adjust the tension of said spring 35, said block 36 being carried by a bracket 38 secured to the base 17 of the pneumatic 7.

In an application filed by me May 11, 1908, Serial No. 432,200, I have shown a pressure regulator embodying an arrangement similar to the spring arrangement of the springs 31 and 35 and a valve arrangement similar to the arrangement of the valve 21 and have set forth and claimed said arrangements in said other application.

Thus it will be seen that, in operation, perforations in a traveling music sheet will first open the extra or rear ports 3, 3 and will then open the usual ports 2, 2 to cause the sounding of notes, the latter being done by means of the ports 2, 2 and playing mechanism in the usual way. When ports 3, 3 are opened, atmospheric air will be admitted into the duct or passage 4 and thence into the tube 6 and into the interior of the pneumatic 7. This will cause or tend to cause an expansion of said pneumatic 7, under the influence of spring 35 and a movement of valve 15 to open or further open port 19. Obviously, varying numbers of note perforations will open varying numbers of ports 3-3 and the quantity of air admitted to pneumatic 7 will therefore vary accordingly. I prefer to have pneumatic 7 and bleed 15^a so constructed that the pneumatic will remain collapsed and valve 15 remain closed when three or four notes are to be sounded. To accomplish this, I make bleed 15^a large enough to permit the air from three or four open ports 3-3 to be drawn therethrough. When a greater number of notes are to be sounded, the air admitted through the greater number of ports 3-3 cannot be taken care of by bleed 15^a, whereupon an expansion of the pneumatic 7, under the influence of spring 35, takes place and valve 15 is opened to a position

which permits the greater quantity of air entering through tube 6 to pass through port 19. Thus, during operation of the device, the position of valve 15 and of swinging leaf 8 is always determined by and will indicate the number of open ports 3-3 greater than three or four. The various positions of swinging leaf 8 thus obtained (through variations in the number of open ports 3-3) act, through the swinging of link 25 upon its pivotal connection with arm 26, to adjust link 23 and valve 21 and, since pneumatic 7 and one end of arm 26 are mounted upon swinging leaf 10, such adjustment of valve 21 will be relative to the swinging leaf 10. An expansion of pneumatic 7 and a consequent adjustment of valve 21 nearer to swinging leaf 10 opens or further opens port 22 and permits a further reduction of pressure in pneumatic 9 which effects a further collapse of that pneumatic, moving swinging leaf 10 and thereby placing greater strain upon spring 31 until valve 21 has been restored to its proper position, throttling port 22. The construction and adjustment of springs 31 and 35 are such that the various positions of swinging leaf 10 thus automatically provided under the control of the note perforations will insure the proper air pressure in pneumatic 9 for the varying numbers of notes represented by those perforations.

Thus there is an automatic adjustment of the pressure to the needs or requirements of the apparatus, which in this case is understood to be the action of the player piano or piano player. It will be noted that, in the operation of the device, when the music sheet is on the tracker with no perforations in register with the apertures 2, 2 and 3, 3, and when at such time the pumping or other wind inducing mechanism is operated, the air will be exhausted to a greater or less degree from the striking pneumatics by way of the ports 30 and 22 and pneumatic 9, and then the valve 21 will be drawn shut and held in that position. When now a few perforations in the music sheet, say for example, three, come into register with the ports 3, 3 and a small amount of air is admitted to the duct 4, and pneumatic 7 by way of tube 6, as previously stated, this amount of air is insufficient to expand the pneumatic 7 because the air can escape through the bleed 15^a in the valve 15, or looked at in another way, the bleed 15^a is sufficiently large to vent the slight excess pressure in the pneumatic 7 without allowing said slight excess pressure to have any effect in expanding said pneumatic 7. The air from pneumatic 7, or the slight excess pressure, however the matter may be considered, being communicated into the interior of the pneumatic 9 by way of bleed 15^a, causes a very slight opening movement of pneumatic 130

9 because, as will be seen, the valve 21 has no accessible bleed, said valve being part of the pneumatic 21^b. This slight opening movement of the pneumatic 9 causes a slight 5 opening of the valve 21 because of the mounting of the pneumatic 7 and associated valve adjusting devices upon the swinging leaf of said pneumatic 9. At this time there is within said pneumatic 9 a degree of pressure 10 sure sufficient to sound the three notes with the desired degree of strength. When now the three perforations of the music sheet come into register with the ports 2—2, said notes will be sounded and the air in the 15 striking pneumatics of said notes will be exhausted into the action chest or other suitable chamber, and will then be exhausted through the regulating apparatus disclosed herein, said air, or the increase of pressure, 20 therefrom being communicated to the port 30 and thence into the interior of the pneumatic 9. When this takes place, the pneumatic 9, under the influence of spring 31, is instantaneously opened a moderate 25 amount, thereby permitting the air to escape from within the pneumatic 9, or looked at the other way, allowing the pressure therein to be again reduced by the opening of the valve 21, upon which the pneumatic 9 30 will be instantly and automatically restored to its former position with the valve 21 closed. If three notes are again sounded, the same series of movements will take place. If, however, a materially greater number of 35 notes are to be sounded, say for example, ten, the air admitted into the ten ports 3, 3 will cause a substantial opening movement on the part of the pneumatic 7, thereby causing substantial opening movements 40 on the parts of the valves 15 and 21. This partially unthrottles the port 22 and permits the establishment of a greater degree of exhaustion within the pneumatic 9, such degree of exhaustion as is sufficient to sound 45 the ten notes with the same force as the previously mentioned three notes were sounded, Pneumatic 7 and valve 15 will remain in the positions just described as long as the number of open ports 3—3 remains unchanged 50 but valve 21 will be instantly returned, through the further reduction of pressure in pneumatic 9 and the consequent closing movement of leaf 10, as hereinbefore described, to properly throttle port 22, so 55 that said pneumatic 9, immediately prior to the sounding of the notes, is in approximately a closed condition with the proper strain upon spring 31 and with the proper degree of pressure therein to sound the number 60 of notes about to be sounded with the desired strength. Upon the opening of the ten ports 2—2 to sound these ten notes, the ten note-sounding pneumatics are sufficiently exhausted by the degree of pressure 65 established in the action chest through port

30 and, immediately upon or after the operation of said note-sounding pneumatics, the air from within the same enters pneumatic 9 through port 30. Pneumatic 9, under the influence of spring 31, and valve 21 are instantaneously opened so that the air entering pneumatic 9 from the ten note-sounding pneumatics is immediately withdrawn through port 22, pressure is instantly reduced again in said pneumatic and valve 21 is instantly returned to its approximately closed position, unless a new adjustment thereof is already required. Thus it will be seen the apparatus controls the pressure to supply the needs of the instrument, in this case a piano player or player piano action, with accuracy and precision, and brings about this control in such a way that the needs or requirements of the instrument are, as it were, anticipated or predetermined and the pressure adjusted in advance. It will also be seen that, after any operation to adjust pressure, the apparatus will be quickly restored to condition for further operation.

Of course, the adjustments of valve 21 and the resulting movements of swinging leaf 10 are substantially simultaneous and, as a consequence, port 22 is rarely, if ever, opened very much by even pronounced expansive movements of pneumatic 7. Likewise, pneumatic 7 is responsive to such a degree that the proper adjustments of leaf 10 are obtained even when note perforations pass with great rapidity across ports 3—3 and 2—2. Should it be possible, however, to pass such perforations across the two sets of ports so rapidly as to not allow time for adjustment of leaf 10, the response of pneumatic 7 in positioning valve 21 in accordance with the number of opened ports 3—3 will be at least as immediate as the response of the note-sounding pneumatics controlled through note-apertures 2—2 and port 22 will thus be properly adjusted in time for the passing of the different volume of air through port 30 and pneumatic 9. Under most conditions, therefore, the adjustment of valve 21 will be sufficiently prior to the operation of the note-sounding pneumatics to cause an adjustment of pressure and a storing of such adjusted pressure in pneumatic 9 but there may be occasions when, as I have described, the operation of the note-sounding pneumatics is so nearly simultaneous with the adjustment of valve 21 that such an adjustment of the valve causes an adjustment of flow without necessarily varying the pressure.

The rod 29 is extended up to some convenient point for manual operation or connected with some device for manual or other desired control, so as to permit an adjustment of the arm 26 so as to control the air pressure on the action by adjusting the link 25 and valve 21. This allows any de-

sired air pressure to be established by the rod 29, and then there will be automatic adjustment with reference to this predetermined pressure for varying numbers of the 5 notes or other requirements.

Fig. 2 illustrates an arrangement more especially adapted for use in connection with a motor, the arrangement of Fig. 1 being well adapted for use in connection 10 with an action. The arrangement of Fig. 2 is quite similar to that of Fig. 1, the tube 6 being understood to be extended to the tracker and connected with special ports 3, 3 therein, just as in the case of Fig. 1. 15 The rest of the mechanism is also the same as that of Fig. 1, in many respects, but there are some differences. The rod 29 and its co-operating link 25 and arm 26 are, for example, not present in Fig. 2, and, furthermore, 20 the swinging leaf 8 of the pneumatic 7 is provided with a strip 8^a which projects beyond the end of the swinging leaf 8, and to the end of this strip 8^a is connected the rod 23 which extends to the valve 21. Thus 25 it will be seen that the arrangement of Fig. 2 operates in a reverse manner to that of Fig. 1, the pneumatic 7 closing the valve 21 when a larger number of the ports 3, 3 is opened and opening said valve 21 as the 30 number of ports 3, 3 is decreased. This brings about proper regulation for the motor, inasmuch as the motor needs less pressure to drive it when there is a larger number of ports 3, 3 and 2, 2 open, there being 35 at such time less suction on the music sheet than when only a few of the ports 3, 3 and 2, 2 are open.

Referring to the arrangement shown in Fig. 3, it will be seen that this arrangement 40 is substantially that shown in Fig. 1, except that the manual or other controlling rod 29 with co-operating arm 26 is not present. The arrangement of Fig. 3 therefore will operate as the arrangement of Fig. 1, but 45 will not permit the alteration of the predetermined air pressure as in Fig. 1.

Referring to Fig. 4, I show a pneumatic 40 corresponding to the pneumatic 9 of the preceding figures, and a second pneumatic 50 41 corresponding to the small pneumatic 7 of the preceding figures. The two pneumatics 40 and 41 are not mounted together as in the preceding arrangements, but are separated from each other. The pneumatic 55 40 contains a slide valve 42 which is connected by a link 43 with the movable leaf of the pneumatic 40, said link 43 being pivoted at one end to the valve and at the other end to the movable leaf of the pneumatic. 60 The device is also provided with a slide valve seat 42^a having a port 42^b, and said slide valve seat 42^a is connected by a rod 44 with a bell crank 45 which is in turn connected with a rod or link 46 extending 65 to and connected with a projection or ex-

tension 47 of the movable leaf 48 of the pneumatic 41. A spring 49 is connected to the movable leaf of the pneumatic 40, said spring 49 tending to hold said pneumatic open. A spring 50 is connected with the leaf 48 of the pneumatic 41, the spring 50 tending to hold said pneumatic 41 open. Within the pneumatic 41 is the valve 15, the same as in the other arrangements. A tube 52 is in communication with the interior of the pneumatic 41, said tube 52 corresponding to the tube 6 of the preceding arrangements. Another tube 51 connects the interior of the pneumatic 41 with the pressure reducing apparatus.

This arrangement operates in a manner substantially similar to that previously described in connection with the other arrangements. It will be noted, however, that for a small number of notes, where the air 85 coming from the supplemental tracker ports 3, 3 is insufficient to actuate the small pneumatic 41, the large pneumatic 40 is not actuated as is the large pneumatic 9 of the preceding arrangements. On the contrary, the 90 small amount of air from three tracker ports 3, 3, or the small excess pressure from the same, will be exhausted or vented directly from the tube 52 to the tube 51 by way of the bleed 15^a. In other respects, the operation 95 of the apparatus will be the same, a relatively large number of note perforations coming into register with the ports 3, 3 causing an expansion of the pneumatic 41, which in turn causes a movement of the 100 valve seat 42^a so as to move the port 42^b therein from under the valve 42 thus opening communication of port 22 with pneumatic 40 to properly adjust the degree of pressure 105 within the pneumatic 40, whereupon the pneumatic 40 itself collapses sufficiently to cause the valve 42 to follow up and close the port 42^b in said valve seat 42^a and thereby close said port 22.

Referring next to Fig. 5, this arrangement 110 is very similar to that of Fig. 4, in so far as the general arrangements of pneumatics 40^a and 41^a are concerned, the swinging leaf of pneumatic 40^a, however, being connected with the swinging leaf of pneumatic 41^a by spring 55. The pneumatic 40^a contains a pivoted lever 56 operating a valve 57 which controls the port 22 in the board 59, the lever 56 being operated directly by the swinging leaf 60 of pneumatic 40^a. A spring 61 is connected with the swinging leaf of pneumatic 41^a, tending to hold said pneumatic open. In this arrangement the pressure adjustment is obtained by the increased tension placed upon spring 55 by an expansion of 115 pneumatic 41^a through the opening of the relatively large number of supplemental tracker ports. In such case it will be understood that the tracker ports 2, 2 and 3, 3 are 120 sufficiently close together to permit the per- 130

forations of the music sheet to maintain the ports 3, 3 open until the ports 2, 2 are also open, so that there shall be no closure of ports 3, 3 until the corresponding ports 2, 2 are opened, in which way the pneumatic 41^a will be maintained in its expanded condition until the notes are sounded.

In this figure I also show a pneumatic action 97 connected with the windway 98 which communicates with the port 30. The 10 form of action shown has a valve 99 on a spindle 100 running to a pneumatic 101, controlled by a tube 102, which is understood to run to the tracker. The pneumatic action 15 97 is shown controlling a piano action having a sticker 103, a hammer 104, and a string 105, the wippen 106 being actuated by a pneumatic 107.

In Fig. 6 I have shown the pneumatic 7 controlling the port 62 of a side passage 63 of the windway 64 and have also shown a valve 65 in said wind way connected by a link 66 with the swinging leaf 8 of the pneumatic 7, so that said pneumatic 7 also controls said valve 65. A spring 67 tends to hold said pneumatic 7 normally open. By this arrangement an expansion on the part of the pneumatic 7 causes an adjustment of the valve 65 and thereby a control of the 25 windway 64, this control being by a windway valve as seen, instead of by a valve within a pneumatic forming part of the apparatus as in the preceding arrangements.

In Fig. 7 I have shown an arrangement 35 somewhat similar to that of Fig. 6, Fig. 7 having the pneumatic 7 controlling a side passage 63 and also controlling a valve 65 in a windway from which the passage 63 extends. In Fig. 7, however, the windway 40 64^a, from which the passage 63 extends, is a branch windway of the main windway 69. This windway 69 is subject to control by another regulator or controller which is a form of controller heretofore employed, the 45 same having a pneumatic 70 communicating by port 71 with the windway 69 and having a valve 72 controlled by the pneumatic 70. Thus there is automatic regulation of the wind in the branch windway 64^a in accordance 50 with my invention, and also regulation by means of the controller-pneumatic 70.

Referring to Fig. 8, I show in this figure an arrangement embodying my invention and adapted for use in connection with electrically operated player pianos or like devices. In this arrangement I show two metallic bars 75 and 76 serving as tracker bars or members, and a music sheet 77 having perforations 78 being drawn over the 60 same. I also show two other bars 79 and 80, whereof the bar 79 is provided with a series of metallic contact fingers 81 which are all connected with it, so that said fingers 81 are in effect connected with one another. 65 The bar 80 is of insulating material and is

provided with fingers 82. The fingers 81 and 82 are adapted to enter perforations 78 in the traveling music sheet 77, so that the fingers 81 and 82 may make contact with their respective bars 75 and 76. A conductor 83 is connected with a solenoid 84, whose core 85 has its lower end submerged in a mercury cup 86. The upper end of the core 85 is suspended from a spring 87, and a conductor 88 is connected with said core 85 and 70 extended thence to a battery 89. An actuating magnet 90 is shown under the piano key 91, the latter having an armature 92 which is attracted when the magnet 90 is energized so as to cause the actuation of the key 91 and consequent playing of the instrument. The magnet 90 is connected by a conductor 93 with one of the fingers 82, it being understood 75 that other keys of the instrument are provided with similar magnets 90 which are connected with other fingers 82. A conductor 94 extends from the battery 89 and is branched at 95 and 96, which branches are connected with the bars 75 and 76, respectively. 80

In the operation of this mechanism, it will be seen that, as the music sheet 77 advances and the fingers 81 enter the perforations 78 in said music sheet, said fingers close a circuit through conductor 83, solenoid 84, conductors 83^a and 88, and battery 89, from which connection is made to bar 75 by conductors 94 and 95. The current passing through the solenoid 84 energizes the same and thereby causes the core 100 85 to descend farther into the mercury cup 86. This of course reduces the resistance of the core 85. Obviously, the greater the number of perforations passing over the bar 75, the greater the number of fingers 105 81—81 caused to make contact with the bar 75, whereby a larger amount of current is passed through the solenoid 84 according to the number of perforations passing over the bar 75, and thereby the greater distance 110 will the core 85 be forced down into the mercury cup 86. When, therefore, the music sheet perforations pass over the bar 76, the fingers 82—82 enter the same, causing corresponding magnets 90 to actuate 115 the corresponding keys 91. The amount of current to be distributed to this larger number of magnets will be greater, whereby each magnet may have the same amount of current and operate with the same power, notwithstanding 120 the number of magnets operated. Thus it will be seen that the power of the playing, or operation of the instrument, is controlled in this arrangement in substantially the same manner as in preceding 125 arrangements.

It will be understood that, while I have herein shown the invention applied to a certain kind of musical instrument, the invention is not to be limited to such instru- 130

ment nor music sheet instruments at all, but is applicable to a wide variety of instruments, devices and apparatus of various kinds and natures.

5. It will be understood that changes and modifications can be made without departing from the spirit of the invention.

What I claim is:

1. The combination of means for determining the number of notes to be sounded and means for varying the power in proportion to variations in the number of said notes, said power varying means being arranged to operate to determine the power prior to the sounding of the notes.

10. 2. The combination of means for determining the number of notes to be sounded and means for controlling the power so that the power available for each such note shall be automatically maintained substantially uniform when the number of such notes is varied.

15. 3. The combination of means for determining the number of notes and means whereby the power is varied in proportion to the number of such notes so that each such note shall have the same amount of power irrespective of the number of such notes.

20. 4. The combination of means for determining the amount of the load and means for varying the power in accordance with variations in the load, said power varying means being provided with mechanism whereby it is adjusted prior to the variation in the load.

25. 5. The combination of a device for controlling fluid pressure, a second device susceptible to and operable by variations in fluid pressure to any degree of adjustment between its extremes, said second device being arranged to operate and control said pressure controlling device, means for varying the load, and means whereby prior to variations in the load said second device is supplied with fluid pressure varying in degree in proportion to such variations in the load.

30. 6. In automatically controlled apparatus, the combination with power operable devices and a moving controller having selective means for controlling the occasion of operation of said devices, of means for adjusting the operating power for said devices, said means being automatically controlled by said controller to cause adjustments of power in time to affect the operation of said devices, the variations in adjustment always corresponding to variations in the number of said devices to be operated.

35. 7. In automatically controlled apparatus, the combination with power operable devices and a moving controller having selective means for controlling the occasion of

operation of said devices, of means for adjusting the operating power for said devices, said means being automatically controlled by said controller to cause adjustments of power in time to affect the operation of said devices, such adjustments always corresponding to the number of the selective means of said controller which are to be simultaneously active in controlling the occasion of operation of said devices. 75

8. In automatically controlled apparatus, the combination with power operable devices and a moving controller having selective means for controlling the occasion of operation of said devices, of means for adjusting the operating power for said devices, said means being automatically controlled by said controller to cause adjustments of power in time to affect the operation of said devices, such adjustments being 80 determined by the number of the selective means of said controller which are to be simultaneously active in controlling the occasion of operation of said devices. 85

9. In automatically controlled apparatus, the combination with power operable devices and a moving controller having selective means for controlling the occasion of operation of said devices, of means for adjusting the operating power for said devices, said means being automatically controlled by said controller to cause adjustments of power in time to affect the operation of said devices, such adjustments being effected by variations in the number of the selective means of said controller which are to be simultaneously active in controlling the occasion of operation of said devices. 95

10. In automatically controlled apparatus, the combination with power operable devices, a moving controller having selective means for controlling the occasion of operation of said devices, and a regulator for adjusting the operating power for said devices, of means coöperating with said regulator and automatically controlled by said controller to cause adjustments of power in time to affect the operation of said devices, the variations in adjustment always corresponding to variations in the number of said devices to be operated. 105

11. Pressure regulating mechanism comprising a tracker having two sets of apertures, whereof the apertures of one set are connected with one another, a device having 110 a connection with said connected set of apertures, and a controlling device controlled by said first mentioned device. 120

12. Pressure regulating mechanism comprising a valve controlling a wind passage 125 or port, a pneumatic for controlling said valve, and means for supplying variable air pressure to said pneumatic, said means comprising a tracker having a series of connected ports connected with said pneumatic. 130

13. Pressure regulating mechanism comprising main and supplemental pneumatics, whereof the supplemental pneumatic is mounted upon the movable leaf of the main pneumatic, a valve arranged within the main pneumatic, said valve controlling a port or passage communicating with the interior of said pneumatic, connections between said valve and the swinging leaf of said supplemental pneumatic, whereby the movement of the latter actuates said valve, and means controlled by the music sheet for supplying variable pneumatic pressure to said supplemental pneumatic.
14. Pressure regulating mechanism comprising main and supplemental pneumatics, whereof the supplemental pneumatic is mounted upon the movable leaf of the main pneumatic, a valve arranged within the main pneumatic, said valve controlling a port or passage communicating with the interior of said pneumatic, connections between said valve and the swinging leaf of said supplemental pneumatic, whereby the movement of the latter actuates said valve, and means for supplying variable pneumatic pressure to said supplemental pneumatic, said means comprising a tracker having a series of connected ports connected with said pneumatic.
15. Pressure regulating mechanism comprising main and supplemental pneumatics, whereof the supplemental pneumatic is mounted upon the movable leaf of the main pneumatic, a valve arranged within the main pneumatic, said valve controlling a port or passage communicating with the interior of said pneumatic, connections between said valve and the swinging leaf of said supplemental pneumatic, whereby the movement of the latter actuates said valve, and means for supplying variable pneumatic pressure to said supplemental pneumatic, said means comprising a tracker having a series of connected ports connected with said pneumatic.
16. Apparatus of the class specified comprising a main pneumatic containing a valve controlling a port communicating with the interior of said pneumatic, a supplemental pneumatic mounted upon the swinging leaf of said main pneumatic and having a port leading from the interior of said supplemental pneumatic to the interior of said main pneumatic, a valve controlling said port, a connection between said valve and the swinging leaf of said supplemental pneumatic, a link having one end connected with the swinging leaf of said supplemental pneumatic and the other end provided with a connection to the valve in said main pneumatic, and a controlling lever connected at one end to the swinging leaf of said main pneumatic, said link having a pivotal connection with said controlling lever.
17. Apparatus of the class specified comprising a main pneumatic containing a valve controlling a port communicating with the interior of said pneumatic, a supplemental pneumatic mounted upon the swinging leaf of said main pneumatic and having a port leading from the interior of said supplemental pneumatic to the interior of said main pneumatic, a valve controlling said port, a connection between said valve and the swinging leaf of said supplemental pneumatic, a link having one end connected with the swinging leaf of said supplemental pneumatic and the other end provided with a connection to the valve in said main pneumatic, a controlling lever connected at one end to the swinging leaf of said main pneumatic, said link having a pivotal connection with said controlling lever, and a tracker having a series of ports connected with one another and connected with said supplemental pneumatic.
18. The combination with a tracker and music sheet, of pressure regulating mechanism controlled from said tracker by the note perforations of said sheet to control the pressure in accordance with the number of notes sounded.
19. The combination with a tracker and music sheet, of pressure regulating mechanism, and connections between said tracker and said regulating mechanism whereby the regulating mechanism is actuated by the note perforations of said sheet in advance of and in accordance with the number of notes to be sounded.
20. The combination with means for determining the number of devices to be operated, of means for automatically securing uniformity of operation of said devices, irrespective of the number operated.
21. The combination with a tracker having a series of note ports and also having supplemental ports, and a music sheet having note perforations, of pressure regulating mechanism connected with the supplemental ports and controlled by the note perforations in the music sheet to vary the pressure in accordance with variations in the number of note perforations in use.
22. The combination with a tracker having a series of connected ports, of pressure regulating mechanism, and means whereby said mechanism is controlled by said connected ports.
23. The combination with a tracker having front and rear sets of ports, whereof the ports of one set are connected with one another, of pressure regulating mechanism, and means whereby said mechanism is controlled by said connected ports.
24. The combination with a tracker having two sets of ports, whereof the ports of

one set are connected together, of pressure regulating mechanism controlled by said set of connected ports, the set of ports by which said regulating mechanism is controlled being situated so as to be reached by the perforations in the traveling sheet before the other set of ports.

25. The combination with a tracker having two sets of ports, whereof the ports of one set are connected together and are situated so as to be reached by the perforations in the traveling music sheet before the ports of the other set are reached by the same, of pressure regulating mechanism connected with said set of connected ports.

26. In automatically controlled apparatus, the combination with power operable devices, a moving controller having selective means for controlling the occasion of operation of said devices, and a regulator for adjusting the operating power for said devices, of means coöperating with said regulator and automatically controlled by said controller to cause adjustments of power in time to affect the operation of said devices, such adjustments always corresponding to the number of the selective means of said controller which are to be simultaneously active in controlling the occasion of operation of said devices.

27. The combination with means for determining the number of devices to be operated, of means for automatically maintaining substantially constant the power applied to each device, irrespective of the number of devices to be operated.

28. The combination with a tracker having a set of connected ports, pneumatic mechanism having a pressure regulating valve, said pneumatic mechanism being connected with and operable from said set of connected ports, whereby the pneumatic pressure is regulated in accordance with the number of said connected ports opened, and means for adjusting said valve independently of said pneumatic mechanism.

29. The combination with a tracker having a set of connected ports, pneumatic mechanism having a pressure regulating valve, said pneumatic mechanism being connected with and operable from said set of connected ports, whereby the pneumatic pressure is regulated in accordance with the number of said connected ports opened, and means for adjusting said valve independently of said pneumatic mechanism, said means comprising a rod arranged for manual manipulation and connected with said valve.

30. The combination with a tracker, of pressure operable mechanism, pressure regulating apparatus, and means whereby said apparatus is controlled from the tracker to vary the pressure for said mechanism in accordance with the number of apertures ex-

posed in the tracker, and whereby such variation in pressure is effected at least as early as the operation of said mechanism.

31. The combination with a tracker, of pressure operable mechanism controlled from said tracker, pressure regulating apparatus, and means whereby said apparatus is controlled from the tracker to vary the pressure for said mechanism in accordance with the number of apertures exposed in the tracker, and whereby such variation in pressure is effected at least as soon as the separate controlling effects of said tracker upon said pressure operable mechanism.

32. The combination with a tracker, of pressure operable mechanism, pressure regulating apparatus, and means whereby said apparatus may be controlled from the tracker in accordance with the number of note apertures exposed and in advance of the exposure thereof.

33. In combination with a tracker and music sheet, a fluid-controlled power regulating device, and means controlled through the apertures of said tracker for varying the regulation of power by said device in accordance with the number of apertures exposed.

34. In combination with a controlling sheet and a tracker, a fluid-controlled power regulating device, and means controlled by the note perforations of said sheet for varying the regulation of power by said device before the note perforations effect the sounding of notes.

35. In combination with sheet-controlled apparatus, a controlling sheet having means arranged to control the actuation of said apparatus, a power regulating device, and means through which the apparatus-controlling means in or upon said sheet may control said device to effect changes in power prior to the actuation of said apparatus.

36. The combination of means for determining the number of pneumatic devices to be operated and means for automatically controlling the pneumatic pressure for operating said devices in accordance with the changes in the number of devices to be operated and in time to affect their operation.

37. The combination of means for determining the number of pneumatic devices to be operated and means for automatically controlling the pneumatic pressure for operating said devices to any degree between extremes in accordance with the changes in the number of devices to be operated, said second mentioned means being arranged to operate in advance of the operation of said devices.

38. Apparatus of the class specified comprising in combination, a plurality of pneumatically operated devices and means comprising the tracker and traveling music

sheet for automatically effecting an advance adjustment of pneumatic pressure to secure uniformity of operation of said devices when the number of devices in operation 5 varies.

39. Pressure regulating mechanism comprising main and supplemental pneumatics, a valve arranged within the main pneumatic, said valve controlling a port or passage communicating with the interior of said pneumatic, connections between said valve and the swinging leaf of said supplemental pneumatic, whereby the movement of the latter actuates said valve, and means 10 for supplying variable pneumatic pressure to said supplemental pneumatic, said means comprising a tracker having a series of connected ports connected with said pneumatic.

40. Pressure regulating mechanism comprising main and supplemental pneumatics, a valve arranged within the main pneumatic, said valve controlling a port or passage communicating with the interior of said pneumatic, connections between said 15 valve and the swinging leaf of said supplemental pneumatic, whereby the movement of the latter actuates said valve, means for supplying variable pneumatic pressure to said supplemental pneumatic, and a valve 20 arranged within said supplemental pneumatic and actuated by the movable leaf thereof, said valve controlling a passage leading from the interior of said supplemental pneumatic to the interior of said 25 main pneumatic.

41. Apparatus of the class specified comprising a main pneumatic containing a valve controlling a port communicating with the interior of said pneumatic, a supplemental 40 pneumatic having a port leading from the interior of said supplemental pneumatic to the interior of said main pneumatic, a valve controlling said port, a connection between said valve and the swinging leaf of said 45 supplemental pneumatic, a link having one end connected with the swinging leaf of said supplemental pneumatic and the other end provided with a connection to the valve in said main pneumatic, and a controlling 50 lever connected at one end to the swinging leaf of said main pneumatic, said link having a pivotal connection with said controlling lever.

42. Apparatus of the class specified comprising a main pneumatic containing a valve controlling a port communicating with the interior of said pneumatic, a supplemental pneumatic having a port leading from the interior of said supplemental pneumatic to 55 the interior of said main pneumatic, a valve controlling said port, a connection between said valve and the swinging leaf of said supplemental pneumatic, a link having one end connected with the swinging leaf of said supplemental pneumatic and the other end 60

provided with a connection to the valve in said main pneumatic, a controlling lever connected at one end to the swinging leaf of said main pneumatic, said link having a pivotal connection with said controlling 70 lever, and a tracker having a series of ports connected with one another and connected with said supplemental pneumatic.

43. Apparatus of the class specified comprising a tracker having a set of note apertures, in combination with means whereby a music sheet having note perforations for said note apertures in the tracker may, through the instrumentality of said note perforations, adjust the pneumatic pressure 75 available for sounding notes in accordance with the number of note sounding devices brought into operation by the music sheet.

44. Apparatus of the class specified comprising a tracker having a set of note apertures, in combination with means whereby a music sheet having note perforations for said note apertures in the tracker may, through the instrumentality of said note perforations, adjust the pneumatic pressure 80 available for sounding notes so as to secure uniformity when different numbers of notes are sounded.

45. The combination with a tracker having a series of note ports and also having a 90 series of supplemental ports corresponding to and in the rear of the note ports, said supplemental ports being connected together, of regulating mechanism connected with said connected ports.

46. In automatically controlled apparatus, the combination with power operable devices, a moving controller having selective means for controlling the occasion of operation of said devices, and a regulator for adjusting the operating power for said devices, of means coöperating with said regulator and automatically controlled by said controller to cause adjustments of power in time to affect the operation of said devices, 100 such adjustments being determined by the number of the selective means of said controller which are to be simultaneously active in controlling the occasion of operation of said devices.

47. In automatically controlled apparatus, the combination with power operable devices, a moving controller having selective means for controlling the occasion of operation of said devices, and a regulator 105 for adjusting the operating power for said devices, of means coöperating with said regulator and automatically controlled by said controller to cause adjustments of power in time to affect the operation of said devices, 110 such adjustments being effected by variations in the number of the selective means of said controller which are to be simultaneously active in controlling the occasion of operation of said devices.

48. The combination with an element to be adjusted, of a device for adjusting said element comprising a pressure chamber having a movable wall, two passages to said chamber, and a valve controlling one of said passages, said element and valve being arranged for adjustment by movement of said wall.

49. The combination with a valve, of a device for adjusting said valve comprising a pressure chamber having a movable wall, two passages to said chamber, and a valve controlling one of said passages, both of said valves being arranged for adjustment by movement of said wall.

50. The combination with an element to be adjusted, of a device for adjusting said element comprising a spring and a pressure chamber having a movable wall, two passages to said chamber, and a valve controlling one of said passages, said element, spring, and valve being arranged for adjustment by movement of said wall.

51. The combination with a valve, of a device for adjusting said valve comprising a spring and a pressure chamber having a movable wall, two passages to said chamber, and a valve controlling one of said passages, said spring and both of said valves being arranged for adjustment by movement of said wall.

52. The combination with an element to be adjusted, of a device for adjusting said element comprising a pressure chamber having a movable wall, two passages to said chamber, a valve controlling one of said passages, and means for controlling the pressure within said chamber through the other of said passages, said element and valve being arranged for adjustment by movement of said wall.

53. The combination with a valve, of a device for adjusting said valve comprising a pressure chamber having a movable wall, two passages to said chamber, a valve controlling one of said passages, and means for controlling the pressure within said chamber through the other of said passages, both of said valves being arranged for adjustment by movement of said wall.

54. The combination with an element to be adjusted, of a device for adjusting said element comprising a spring and a pressure chamber having a movable wall, two passages to said chamber, a valve controlling one of said passages, and means for controlling the pressure within said chamber through the other of said passages, said element, spring, and valve being arranged for adjustment by movement of said wall.

55. The combination with a valve, of a device for adjusting said valve comprising a spring and a pressure chamber having a movable wall, two passages to said chamber, a valve controlling one of said passages, and means for controlling the pressure within said chamber through the other of said passages, said spring and both of said valves being arranged for adjustment by movement of said wall.

56. The combination of means for determining the number of notes to be sounded and means for controlling the power so that the power available for sounding each such note shall be controlled prior to the sounding thereof in accordance with the number of notes to be sounded.

57. The combination of means for determining the number of notes to be sounded and means for controlling the power so that the variations in the number of such notes will effect the action of said second mentioned means to provide the proper power to maintain substantially uniform the sounding of each such note.

58. The combination with a tracker, of pressure operable devices controlled in operation from said tracker, pressure regulating apparatus, and means whereby said apparatus may be controlled from said tracker in accordance with the varying numbers of said devices successively controlled in operation from said tracker and in advance of such control.

In witness whereof, I hereunto subscribe my name this 27th day of March, A. D. 1913.

JAMES CLARKE HAGEY.
